(57) **CLAIM**

The ornamental design for an anti-tangle device for flags, as shown and described.

DESCRIPTION

FIG. 1 is a perspective view of the anti-tangle device for flags showing our new design in a position of use;

FIG. 2 is a side elevational view thereof, the opposite side being a mirror image thereof;

FIG. 3 is a rear elevational view thereof;

FIG. 4 is a front elevational view thereof;

FIG. 5 is a top plan view of one component of the anti-tangle device for flags, the bottom plan view being a mirror image thereof;

FIG. 6 is a top plan view of a second component of the anti-tangle device for flags, the bottom plan view being a mirror image thereof; and,

FIG. 7 is an exploded perspective view of the anti-tangle device for flags.

The broken lines in the drawings represent unclaimed environmental subject matter.
